US0D1051994S

(12) **United States Design Patent** (10) Patent No.: **US D1,051,994 S**
(45) Date of Patent: ** Nov. 19, 2024

(54) **GAMING MACHINE WITH INTEGRATED CANDLE**

(71) Applicant: **Aristocrat Technologies Australia Pty Limited**, North Ryde (AU)

(72) Inventor: **Bruce Urban**, Las Vegas, NV (US)

(73) Assignee: **ARISTOCRAT TECHNOLOGIES AUSTRALIA PTY LIMITED**, North Ryde (AU)

(**) Term: **15 Years**

(21) Appl. No.: **29/895,917**

(22) Filed: **Jun. 27, 2023**

CLAIM

The ornamental design for a gaming machine with integrated candle, as shown and described.

DESCRIPTION

This design patent application also incorporates by reference the following applications in their entirety: U.S. patent application Ser. No. 29/698,015, filed Jul. 12, 2019, and U.S. patent application Ser. No. 29/698,554, filed Jul. 17, 2019. All disclosure and subject matter, including all figures, of each of these applications are specifically incorporated by reference in this application as if set forth fully herein.

FIG. 1 is a front perspective view of a gaming machine with integrated candle showing my new design according to a first embodiment;

FIG. 2 is a front elevation view thereof;

FIG. 3 is a right side elevation view thereof;

FIG. 4 is a left side elevation view thereof;

FIG. 5 is a top plan view thereof;

FIG. 6 is a front perspective view of a gaming machine with integrated candle showing my new design according to a second embodiment;

FIG. 7 is a front elevation view thereof;

FIG. 8 is a right side elevation view thereof;

FIG. 9 is a left side elevation view thereof;

FIG. 10 is a top plan view thereof;

FIG. 11 is a front perspective view of a gaming machine with integrated candle showing my new design according to a third embodiment;

FIG. 12 is a front elevation view thereof;

FIG. 13 is a right side elevation view thereof;

FIG. 14 is a left side elevation view thereof;

FIG. 15 is a top plan view thereof;

FIG. 16 is a front perspective view of a gaming machine with integrated candle showing my new design according to a fourth embodiment;

FIG. 17 is a front elevation view thereof;

FIG. 18 is a right side elevation view thereof;

FIG. 19 is a left side elevation view thereof;

FIG. 20 is a top plan view thereof;

FIG. 21 is a front perspective view of a gaming machine with integrated candle showing my new design according to a fifth embodiment;

FIG. 22 is a front elevation view thereof;

FIG. 23 is a right side elevation view thereof;

FIG. 24 is a left side elevation view thereof;

FIG. 25 is a top plan view thereof;

FIG. 26 is a front perspective view of a gaming machine with integrated candle showing my new design according to a sixth embodiment;

FIG. 27 is a front elevation view thereof;

FIG. 28 is a right side elevation view thereof;

FIG. 29 is a left side elevation view thereof; and,

FIG. 30 is a top plan view thereof.

The dashed broken lines in the drawings illustrate portions of the gaming machine that form no part of the claimed design.

The areas of stipple shading in the drawings depict contrasts of appearance and do not depict any particular color, texture, or material.

Views of the gaming machine not shown form no part of the claimed design.
